UNITED STATES PATENT OFFICE.

ELERY GARFIELD, OF ALGONA, IOWA.

FURNACE.

SPECIFICATION forming part of Letters Patent No. 688,845, dated December 17, 1901.

Application filed July 27, 1901. Serial No. 69,909. (No model.)

To all whom it may concern:

Be it known that I, ELERY GARFIELD, a citizen of the United States, and a resident of Algona, Kossuth county, State of Iowa, have 5 invented certain new and useful Improvements in Furnaces; and my preferred manner of carrying out the invention is set forth in the following full, clear, and exact description, terminating with claims particularly specifying the novelty.

This invention relates to stoves and furnaces, and more especially to that class thereof which use hot air as a medium for heating remote apartments; and the objects of the 15 same are to improve and cheapen the details of construction, to utilize as much as possible of the heat generated by the fire, to lessen the production of soot, and to adapt the furnace for heating water when desired.

20 To this end my invention consists in a furnace constructed substantially as hereininafter described and as shown in the accompanying drawings, wherein—

Figure I is a central vertical section of this 25 furnace complete. Fig. II is a cross-section of the same. Fig. III is a perspective view of the furnace with the casing removed.

Referring to the drawings, the numeral 1 designates a casing, which may be of metal 30 or any good non-conductor of heat, and 2 designates the main flue leading from the casing and intended to convey hot air to the remote apartments in the building. Within this casing is located my improved furnace, 35 wherein 3 is the ash-pit, having the usual door 4. 5 is the grate above the ash-pit. 6 is the fire-box, having the usual door 7, and 8 is an inlet-tube extending downward through all the chambers and flues hereinaf- 40 ter described and admitting a blast of air directly upon the coals in the fire-box 6, which blast of air is heated in its descent in a manner which will be clear. In certain cases and when desired I locate a coil 9 above the 45 fire-box and beneath the lowermost air-chamber, hereinafter described, and through this coil may be passed water which is heated by the fire and can be conducted to a remote point for any purpose desired. The inlet and 50 outlet pipes to and from this coil preferably lead through the rear of the casing 1, as best seen in Fig. I.

Within and slightly remote from the sides of the casing are two upright side walls 10, as best seen in Fig. II, and these are connected by horizontal and vertical walls or partitions, so as to form the chambers and flues. (Best seen in Fig. I.)

11 11 are the air-chambers, of which the lowermost and uppermost open toward the 60 front of the casing and the intermediate one opens toward the rear.

12 12 is the smoke-flue, which passes in a tortuous course around the three air-chambers, leading first to the rear from the fire-box, as 65 at 13, then upward behind the lowermost air-chamber, then forward over this chamber and upward in front of the second air-chamber, then rearward over this chamber and upward in rear of the third air-chamber, and 70 finally forward and into what I call the "indirect" draft 14, which communicates with the chimney 15. From the lowermost convolution of the smoke-flue at its front end I lead a direct draft, which is a pipe 16, passing 75 forward through the casing 1 and thence upward, as at 17, and communicating with the chimney 15. The direct draft has a damper 18, whose handle is shown in Fig. III, and the indirect draft has a damper 19. 80

As above stated, the inlet-tube 8 passes downward through all the flues 12 and chambers 11, and the inflowing air therein thus receives its heat, while the pipes to and from the water-coil preferably pass inward through the rear 85 of the casing, and the coil stands just beneath the lowermost air-chamber 11. All the chambers and flues stand slightly remote from the four side walls of the casing, and the uppermost flue is beneath its top, where- 90 by the air has a free circulation entirely around the furnace proper, and when it is heated it is drawn off at 2 and piped to the rooms to be heated.

All parts are of the desired sizes, proportions, and materials, and changes in and additions to the details of construction may be made without departing from the principle 95 of my invention.

What I claim is—

1. In a furnace, the combination with the casing, and the ash-pit, grate, and fire-box within the lower portion thereof; of a smoke-flue following a tortuous course from the up-

- per rear portion of the fire-box, upward, thence forward, thence upward, thence rearward, thence upward, and finally again forward, an indirect-draft pipe leading from the 5 upper extremity of this smoke-flue to the chimney, a direct-draft pipe leading from the lowermost forward bend of this smoke-flue also to the chimney, dampers in these draft-pipes, and three air-chambers located respectively within the bends of the smoke-flue and communicating alternately with the interior of the casing, all substantially as described.
- 10 2. In a furnace, the combination with the casing, and the ash-pit, grate, and fire-box 15 within the lower portion thereof; of a smoke-flue following a tortuous course from the upper rear portion of the fire-box, upward, thence forward, thence upward, thence rearward, thence upward, and finally again forward, an indirect-draft pipe leading from the upper extremity of this smoke-flue to the chimney, a direct-draft pipe leading from the lowermost forward bend of this smoke-flue also to the chimney, three air-chambers located 25 respectively within the bends of the smoke-flue and communicating alternately with the interior of the casing, and a fresh-air tube leading straight downward through all the smoke-flues and air-chambers and delivering its blast of heated air directly onto the fire, all substantially as described.
- 30 3. In a furnace, the combination with the casing, and the ash-pit, grate, and fire-box within the lower portion thereof; of a smoke-flue following a tortuous course from the upper rear portion of the fire-box, upward, thence forward, thence upward, thence rearward, thence upward, and finally again forward, an indirect-draft pipe leading from the 35 upper extremity of this smoke-flue to the chimney, a direct-draft pipe leading from the 40

lowermost forward bend of this smoke-flue also to the chimney, three air-chambers located respectively within the bends of the smoke-flue and communicating alternately with the interior of the casing, and a water-coil located directly beneath the lowermost air-chamber with its inlet and outlet pipes leading rearward through the wall of the smoke-flue and the wall of the casing, all substantially as described.

4. In a furnace, the combination with the casing, and the ash-pit, grate, and fire-box within the lower portion thereof; of a smoke-flue following a tortuous course from the upper rear portion of the fire-box, upward, thence forward, thence upward, thence rearward, thence upward, and finally again forward, an indirect-draft pipe leading from the upper extremity of this smoke-flue to the chimney, a direct-draft pipe leading from the lowermost forward bend of this smoke-flue also to the chimney, dampers in these draft-pipes, three air-chambers located respectively within the bends of the smoke-flue and communicating alternately with the interior of the casing, a fresh-air tube leading straight downward through all the smoke-flues and air-chambers and delivering its blast of heated air directly onto the fire, and a water-coil located directly beneath the lowermost air-chamber with its inlet and outlet pipes leading rearward through the wall of the smoke-flue and the wall of the casing, all substantially as described.

In testimony whereof I have hereunto subscribed my signature this the 24th day of July, A. D. 1901.

ELERY GARFIELD.
